DISPENSING CONTAINER

Edward E. Baker, Larchmont, N. Y., assignor to
 Continental Can Company, Inc., New York,
 N. Y., a corporation of New York

Application May 10, 1940, Serial No. 334,456

2 Claims. (Cl. 221—62)

The present invention relates to new and useful improvements in dispensing containers, and more particularly to improvements in a dispensing container from which the contents thereof may be sifted or poured in bulk.

In general, the invention contemplates the provision of a sheet metal container wherein the body portion is closed at one end thereof preferably by a friction closure which forms the end of the container. The opposite end of the body portion may be closed by an end which is seamed or otherwise suitably secured thereto. The friction closure end fits within and abuts against the inner surface of the body wall of the container and is provided with sifting openings near one end thereof and with a relatively large pouring opening disposed inwardly of the sifting openings. A closure member in the form of a slide is provided for closing the dispensing openings in the container end. In one dispensing position of the slide, the sifting openings may be exposed to permit sifting of the contents, while in another position of the slide, the sifting openings and at least a part of the pouring opening may be exposed to permit pouring of the contents in bulk from the container.

An object of the present invention is to provide a container of the above type wherein the dispensing end of the container fits within the body portion in a position with the outer surface thereof substantially flush with the upper edge of the body wall.

A further object of the invention is to provide a container of the above type wherein a closure member is mounted on the body portion for sliding movement in contact with the top surface of the dispensing end so as to prevent the accumulation of matter therebetween.

A still further object of the invention is to provide a container of the above type wherein the body wall is outwardly beaded at the top thereof for permitting the slidably mounting thereon of a closure member for controlling the dispensing openings in the dispensing end of the container.

A still further object of the invention is to provide a container of the above type which is simple in construction and which is relatively inexpensive to manufacture.

The above and other objects of the invention will in part be obvious and will be hereinafter more fully pointed out.

In the accompanying drawing,

Figure 1 is a top plan view of the container of the present invention, showing in full lines the

position of the sliding closure for dispensing the contents in bulk, and showing in dotted lines, the position of the sliding closure for sifting the contents of the container.

5 Figure 2 is a fragmentary sectional view, taken along the line 2—2 of Figure 1.

Figure 3 is a fragmentary sectional view, similar to Figure 2, but showing the sliding closure member in a position closing the dispensing openings.

10 Figure 4 is a sectional view taken along the line 4—4 of Figure 1.

Referring more in detail to the accompanying drawing, the container is illustrated as including a substantially rectangular body portion 10, although it is to be understood that the body portion may be of any desired shape. This body portion is provided at the bottom thereof with a closure member (not shown) which may be secured thereto by double seaming or the like. A top closure member 11 is in the form of a dispensing end portion which is fitted within the top end of the body wall. This closure member 11 includes a top horizontal portion 12 and a depending peripheral skirt portion 13 which fits within and preferably frictionally engages the inner surface of the body wall around the top end thereof.

15 Stop means in the form of inwardly extending lugs 14, or an inward shoulder, are provided on the body wall. The bottom edge of the skirt portion 13 of the closure 11 abuts against the stop means so as to limit inward movement of the closure 11 relative to the body wall of the container. The skirt portion 13 and the stop means 14 are constructed and arranged so that the upper face of the top 12 of the closure 11 is substantially flush with the top of the body wall 10. The body wall 10 is provided with an outward bead 15 around the edge thereof, and the uppermost part of this bead is flush with the exposed upper face of the top 12 of the closure 11.

20 The top 12 of the closure member 11 is provided with a group of sifting openings 16 adjacent one edge thereof and with a relatively large pouring opening 17 spaced inwardly of the sifting openings. A closure member in the form of a slide 18 is provided at the sides thereof with depending flanges 19, 19a which extend around and frictionally engage the bead 15 at the sides of the body wall of the container. Thus, the depending flanges 19, 19a cooperate with the bead 15 at the sides of the body wall to slidably mount the closure member 18 on the body portion of the container. One end of the closure member 18 is

also provided with a depending flange portion 20 which serves as a stop cooperating with the portion 15a of the bead 15 at the adjacent end of the container, to limit movement of the closure member 18 to its closed position covering the dispensing openings in the top of the closure member 11.

The closure member 18 is provided with an elevated rib portion 21 which serves as a finger hold for shifting the closure member to its various positions. The closure member 18 is also provided with a depending shoulder 22 which extends into the pouring opening 17 and is movable therein as the closure member 18 is shifted relative to the container. As shown in Figure 3, the closure member 18 is in a closed position covering the sifting openings 16 and the pouring opening 17, and in this position of the closure member 18, the depending flange portion 20 abuts against the portion 15a of the bead 15, and the depending lug or shoulder 22 abuts against the forward edge 11a of the pouring opening 17. When the closure member 18 is shifted to the position shown in dotted lines in Figure 1, the sifting openings 16 will be exposed, thus permitting sifting of the contents of the container. When the closure member 18 is shifted to the position shown in full lines in Figure 1, the depending lug or shoulder 22 thereon will abut against the edge 17b of the pouring opening 17 and serve as a stop limiting further movement of the closure member 18. In this position of the closure member 18, the sifting openings 16 and also a part of the pouring opening 17 will be exposed to permit pouring of the contents of the container in bulk.

From the foregoing description, it will be seen that the upper exposed face of the closure member 11 is substantially flush with the top of the bead 15 on the body wall 10, and the bottom face of the closure member 18 contacts with the upper face of the closure member 17 throughout the extent thereof so as to prevent accumulation of matter between the two closure members and to also serve to provide an effective seal for the dispensing openings when the closure member 18 is in a closed position. The end 18a of the closure member 18 extends over the bead 15, as shown in Figure 3, when the closure member 18 is in its fully closed position.

While one form of the invention has been shown in the accompanying drawing for purposes of illustration, it is to be clearly understood that minor changes in the details of construction and arrangement of parts may be made without departing from the scope of the invention as set forth in the appended claims.

I claim:

1. A dispensing container comprising a body portion rolled outwardly at its upper end into a hollow bead, an end member lying substantially in a plane tangent to the extreme upper portion of the hollow bead and extending to the bead for closing the upper end of said body portion, said end closure member having sifting openings therethrough and a dredging opening therethrough, a flat slide for closing said sifting openings and said dredging opening, said slide contacting with the upper face of said end member and having the side portions thereof rolled beneath the hollow bead so as to slidably connect said closure slide to the container body, means for limiting the movement of the slide when in closed position, and means for limiting the movement of the slide when in open position.

2. A dispensing container comprising a body portion rolled outwardly at its upper end into a hollow bead and having an inwardly projecting bead formed in the body wall a short distance below said hollow bead, an end member for closing the open end of the body portion, said end member having a depending skirt adapted to frictionally engage the inner surface of the body wall, said skirt being dimensioned so that when contacting with the inwardly directed bead in the body wall the closure portion of the end will be flush with the upper edge portion of the hollow bead, said end closure member having sifting openings therethrough and a dredging opening therethrough, a slide for closing said sifting openings and said dredging opening, said slide contacting with the upper face of said end member and having the side portions thereof rolled beneath the hollow bead so as to slidably connect said closure slide to the container body, means for limiting the movement of the slide when in closed position, and means for limiting the movement of the slide when in open position.
